REVERSING VALVE

Original Filed Oct. 31, 1919 2 Sheets-Sheet 2

FIG. 2.

UNITED STATES PATENT OFFICE.

ALBERT T. KELLER, OF BALTIMORE, MARYLAND.

REVERSING VALVE.

Application filed October 31, 1919, Serial No. 834,775. Renewed February 11, 1922. Serial No. 535,948.

To all whom it may concern:

Be it known that I, ALBERT T. KELLER, a citizen of the United States, and a resident of Baltimore, in the county of Baltimore and State of Maryland, have made a new and useful Improvement in Reversing Valves, of which the following is a specification.

My invention relates to regenerative furnaces and consists of a reversing valve adapted to change the direction of flow of fuel or exhaust gases in the flues of the furnace and to vary, if desired, the fluid passed thru the respective flues.

One of the objects of my invention is to provide a device wherein the directing of one gas stream thru certain channels automatically directs another gas stream thru other channels and irrespective of the direction of flow of the various streams. Another object is to prevent the escape of gases to the atmosphere when their flow is reversed. Another object is to provide adequate mechanism for reversing my valve with a minimum of labor and time.

In the accompanying drawings illustrating my invention, Figure 1 is a vertical section thru the stack flue and two regenerative flues of a furnace and thru my reversing valve arrangement and is taken on line 1—1 of Fig. 2; Fig. 2 is a plan view and section on line 2—2 of Fig. 1, and Fig. 3 is a broken vertical section on line 3—3 of Fig. 2.

Briefly, my invention consists of a rotatable tube 1 adapted to connect a flue 2 with a flue 3 or a flue 4 and contained, with the ports of these flues, within a box 5 which is adapted to supply fuel gas or air to the flue 3, or 4, which is not connected to tube 1. In my detailed description I will assume that box 5 supplies one of the regenerator flues with air to be mixed with the fuel gas, introduced elsewhere, in a combustion chamber and that the exhaust gases from the combustion chamber are led thru the other regenerator flue and discharged thru tube 1 and pipe 2 to a stack flue 6. This direction of flow of the particular gases mentioned is only a tentative circulation to demonstrate the operation of my device and is not to be understood as exclusively defining its use.

The ports of flues 3 and 4 terminate in seal troughs 7 and 8 respectively. A vertical line thru a point equidistant from the centers of the circular troughs 7 and 8 forms the axis of my reversing valve and passes

thru the center of the end of pipe 2 which is provided with a seal flange 9. The lower end of a double curved connecting tube 1 terminates in a seal flange 10 adapted to fit in trough 7 and the upper end of the tube is provided with a rim 11 which forms a depending seal flange and an upwardly facing seal trough.

Where the vertical axis intersects the lower face of tube 1, I provide an integral boss 12 on the tube. Boss 12 is recessed and a pin 13, seated in the base of box 5, extends into this recess and forms a pivotal support for tube 1.

A semi-cylindrical box 5 is erected upon the brickwork. It surrounds the ports of flues 3 and 4, encloses tube 1, and is provided on its upper face with a seal trough 14 adapted to receive the depending seal flange 75 on tube rim 11. The upper face of box 5 is also provided with a door 15 which may be opened to admit air to the interior of the box. It will be noted that free communication exists between flue 4 and box 5 and the 80 opening of door 15 supplies a continuous stream of fresh air to the flue.

I reverse the flow of the exhaust gases by revolving tube 1 on its axial pivot 13 to bring its lower end over the port in the latter flue. To accomplish this reversal, three movements are necessary: first, tube 1 must be raised to free flange 10 from the overlapping sides of seal trough 7; second, the tube must be revolved to the reversed position, and third, the tube must be lowered to the new sealed position indicated by the dotted lines in Fig. 1.

The raising and lowering movements are accomplished by means of a lever 16 and a piston 17 operated by fluid pressure in a cylinder 18. Lever 16 is pivoted at 19 in a seal pot 20 and below the lower edge of an extension on box 5 which dips into the seal pot. One arm of lever 16 rises from seal pot 20 and its end forms a collar 21 fitting a groove 22 in boss 12. The other arm of lever 16 rises from seal pot 20 and is attached to the end of piston rod 38 in cylinder 18 attached to a standard 23 mounted on the furnace brickwork. It is obvious that the operation of piston rod 38 thru cylinder 18 will raise and lower tube 1 out of and into sealing relation with the flue ports.

Tube 1 is revolved in alternating directions by a reciprocating rack 24 geared to the tube. Rack 24 is in the form of a hy-

draulic cylinder with rack teeth 25 on one side. The rack slides to and fro in a standard 26 which also forms a journal bearing 27 for a pinion 28 and a gear 29. A stationary piston 30 fits within rack cylinder 24 and is held in the central position by a hollow piston rod 31 secured to standard 23 and a corresponding standard 32. Fluid pressure is admitted alternately to opposite 10 sides of piston 30 in cylinder 24 thru pipes 33 and 34 and ports 35 and 36 respectively in rod 31. As piston 30 is fixed, rack cylinder 24 is moved in the desired direction and rotates pinion 28 and gear 29. The latter 15 meshes with a gear 37 mounted on rim 11 of tube 1. The faces of the teeth on gears 29 and 37 are broad enough to permit relative vertical movement of the gears without becoming unmeshed.

20 Operation: Assume that the checker brick to which flue 4 leads have been cooled by the incoming gases while those at the end of flue 3 have been heated and it is desired to reverse the gas flow. Fluid pressure is admitted to cylinder 18 which raises tube 1, by lever 16, to clear seal trough 7. Fluid pressure is then admitted to cylinder 24 thru pipe 33 and port 35 and the resulting movement of rack teeth 25 rotates pinion 28 and 25 gear 29 in a clockwise direction and gear 37 and tube 1 in the opposite direction on the latter's axis. When the lower end of 30 tube 1 has reached the port of flue 4, the valve (not shown) controlling pipe 33 is 35 closed. The pressure in cylinder 18 is released when tube 1 will lower to sealing po-

sition and the stack draft thru pipe 2 and flue 6 will reverse the direction of both inlet and exhaust gases. The reversal of tube 1 automatically directs the air admitted to box 5 to flue 3 instead of flue 4. If desired, a fuel gas supply pipe may be attached to lead to box 5 and the air admitted to the combustion chamber from another point.

40 My valve may be modified in many respects and duplicate parts added to the illustrated form without affecting the principle of my invention and I contemplate such changes in its commercial development.

45 I claim:—

50 In a regenerative furnace, a stack flue, regenerator flues, a reversing valve box provided with ports to said regenerator flues, a tube having a portion extending outside of said box to said stack flue and a portion 55 inside of said box and extending to one of said ports, a fluid seal between the exterior of said outside portion and said box, a fluid seal between said outside portion and said stack flue, a fluid seal between said inside 60 portion and the port to which it is connected, means operated externally of said box for making and breaking said latter mentioned seal, and mechanism outside of said box for changing the connection of said inside portion 65 to another of said ports; said seal and mechanism functioning as described without breaking said first two mentioned seals.

65 In testimony whereof, I have hereunto 70 subscribed my hand this 27th day of October, 1919.

ALBERT T. KELLER.
